UNITED STATES PATENT OFFICE.

BENJAMIN COLLINS, OF OAKLAND, CALIFORNIA.

MACHINE FOR CUTTING CORN FROM THE COB.

SPECIFICATION forming part of Letters Patent No. 327,864, dated October 6, 1885.

Application filed January 27, 1885. Serial No. 154,159. (No model.)

To all whom it may concern:

Be it known that I, BENJAMIN COLLINS, of 5
Oakland, Alameda county, State of California, have invented certain new and useful Im-
provements in Machines for Cutting Corn from
the Cob, of which the following is a specifica-
tion.

My invention has for its objects the produc-
tion of a simple and efficient machine for cut-
ting off corn from the cob; and my improve-
ments therein relate particularly to the con-
struction of the cutting mechanism, and generally
to the construction and combination of
parts constituting an improved machine for
the purpose, as hereinafter fully described and
claimed.

Referring to the accompanying drawings, 20
Figure 1 is a general view in perspective of
my improved machine. Fig. 2 is a longitudi-
nal view, on a larger scale, and in section, of
the reciprocating cross-head and its cutters.
Fig. 3 is an end view of the cross-head; and
Fig. 4 is a view taken from the under side of
the cross-head.

25 A suitable bench or table, A', with an open-
ing, A², in the top, and a chute, A³, leading
from it, is provided with upright guides A⁴
A⁴, between which a movable cross-head, A,
is made to move up and down by being at-
tached to a vertically-moving rectangular
30 frame, D^x D^x, under the table. This frame
is provided with upwardly-arranged guide-
arms a, which extend inwardly from the re-
spective corners thereof, and are provided at
35 their upper ends with vertical apertures for
the passage of the rods C C, which are con-
nected at their lower ends to the said frame.
The ends B B of the cross-head are fitted into
grooves in the inner faces of the upright guides.

40 By pressing upon the frame the operator
brings down the cross-head toward the table,
and when this pressure is relieved the up-
ward movement is effected by means of cords
b and counter-weights C', as shown in Fig. 1;
but springs may be employed in place of
45 weights for this purpose. The cords b, pass-
ing over pulleys Z, suspended from the under
side of the main frame, are secured at one end
to the vertically-moving frame D, their oppo-
site ends being provided with counterbalance-
50 weights c'.

The cutters are four blades or knives with
straight shanks m m and curved cutting-edges,
so arranged around a common center that they
inclose and form a circle, of which each cutter
55 composes one-quarter or thereabout. The
side cutters, l l, are somewhat smaller in
breadth than the cutters K, and are over-
lapped thereby, as shown. The curved edges
of the cutters are only on the ends of the
60 shanks m, and above these cutting-edges the
shanks are slotted at f for bolts or rivets, by
which they are fixed to adjustable slides E.
These slides are held in the dovetail grooves
of a plate, D, that is fixed to the bottom of
65 the cross-head. They are confined in these
grooves against any lateral movement, but are
free to slide longitudinally, or toward and
away from the center around which the cut-
ters are arranged. A yielding movement of
70 the cutter is afforded by connecting each slide
E to a fixed pin or stud, g, by means of a
coil-spring, i, so applied that its tendency is
always to draw in the carrier-slide E to the
center. Each slide is dovetailed into its grooves,
75 and the spring is attached to the slide by a
pin, h, and to the fixed pin g, that works
through a slot, f, in the slide E, as shown in
Fig. 2.

The cutters thus mounted are self-adjusting,
80 and will adapt themselves to different sizes of
cob, and to any variation in the size of a cob
as they are forced down over it from point to
butt.

85 Directly under the center of the opening in-
closed by the cutters a pin or barb, X, is fixed
in upright position on the table to hold and
present the cob to the cutter. The cob, when
impaled on it, is held upright, while the cross-
head is brought down over it by depressing
90 the treadle or frame D, and as the cutters fol-
low down the sides of the cob and enter be-
tween it and the kernels they accommodate
themselves to the varying size of the cob.

Having thus fully described my invention,
95 what I claim, and desire to secure by Letters
Patent, is—

1. In a machine for cutting corn from the
cobs, the combination, with the head-block,
of the plate D, having the dovetail grooves and
100 studs, the slide E, having studs, the springs
connecting the said plates and slides, and the

knives, arranged and adapted to operate substantially as specified.

2. The combination, with the main frame having the vertical guide-standards, of the cross-head carrying the segmental yielding cutters, the vertically-moving frame D^x , having the bars a , provided with the guide-aper-
tures, the rods connecting the said frame with the cross-head, the guides or pulleys, and the

ropes having counterbalance-weights and con-
nected with the frame D^x , substantially as
shown and described.

In witness whereof I have hereunto set my hand.

BENJ. COLLINS. [L. S.]
